UNITED STATES PATENT OFFICE.

ALFRED A. ZIEGLER, OF BOSTON, MASSACHUSETTS, ASSIGNOR TO UNITED ELECTRIC APPARATUS COMPANY, OF BOSTON, MASSACHUSETTS, A CORPORATION OF MASSACHUSETTS.

ELECTROMAGNET.

1,268,200.

Specification of Letters Patent.

Patented June 4, 1918.

Original application filed September 14, 1908, Serial No. 452,846. Divided and this application filed December 27, 1909, Serial No. 534,932. Renewed March 29, 1918. Serial No. 225,583.

To all whom it may concern:

Be it known that I, ALFRED A. ZIEGLER, of Boston, county of Suffolk, State of Massachusetts, have invented an Improvement 5 in Electromagnets, of which the following is a specification.

This invention relates to electro-magnets and is a division of my application Serial No. 452,846, filed September 14, 1908, and 10 has for its object to construct an electro-magnet especially adapted for use in relays employed for railway signaling purposes.

The invention has for its object an improved construction of support for the magnet-coils, which is made as a bracket, adapted to be removably supported upon a back-board; also improved means for protecting the magnet-coils and for holding them in position on the cores; also connections for 15 the magnet-wires arranged between the coils, whereby either coil may be separately connected in circuit to the exclusion of the other; also an improved support for the armature whereby it may move in an arc of 20 large radius; also an improved adjustable means for limiting the movement of the armature; also the employment of a glass globe to protect the moving parts and improved means for supporting said globe; also the 25 employment of a glass globe for protecting the magnet-coils.

Figure 1 is a front elevation of an electro-magnet embodying this invention.

Fig. 2 is a side elevation of the electro- 35 magnet shown in Fig. 1.

Fig. 3 is a plan view of the bridge at the upper ends of the magnet-coils.

Fig. 4 is a detail of the armature-carrying-plate.

40 Fig. 5 is a sectional detail of one of the pivot-supports for the armature-carrying-plate.

Figs. 6 and 7 are details of one of the 45 pivot-supports for the armature-carrying-plate and the pole-piece which is connected to the core of the magnet.

Figs. 8 and 9 are modified details of the 50 pivot-support for the armature-carrying-plate.

55 Fig. 10 is a plan view of a portion of the supporting-bracket for the magnet.

Fig. 11 is a view illustrating modified means for holding the connecting magnet-wires.

Fig. 12 is a sectional detail of the magnet- 55 support.

Fig. 13 is a view showing means for holding the magnet-coils in position.

Fig. 14 is a sectional detail of the base of the supporting-bracket, showing the con- 60 nection of the glass globe therewith.

Fig. 15, is a front view of the electro-magnet having glass globes both above and below the base.

Figs. 16 and 17 are modified forms of the 65 inclosing-case for the moving parts of the electro-magnet.

a represents the base of a supporting-bracket, and *a'* the upright thereof which rises from one edge, as for instance from 70 the rear edge of the base, and, as here shown, extends from side to side thereof. The base may be hinged to the upright, as shown in Fig. 2, or formed integral therewith, as shown in Figs. 10 and 15. The upright *a'* 75 has keyhole or other shaped slots *a*² adapted to receive headed-studs *a*³, projecting from the face of a back-board *a*⁴, said slots and studs permitting the bracket to be easily and quickly applied to and removed from the 80 back-board.

The upright *a'* is recessed at its rear side, see Fig. 10, to provide spaces between it and the back-board, which extend from top to bottom of the bracket, to receive the electric- 85 wires, it being herein shown as having two vertical recesses *a*⁵, *a*⁶, arranged a short distance apart. The intermediate portion between said recesses has a downwardly ex- 90 tended portion *a*⁶, see Fig. 2.

The magnet-coils *b* are arranged on top of the base *a*, and the cores *b'* thereof are extended through holes in said base, see Fig. 6, and preferably project a short distance below it, and to the projecting ends of said 95 cores, pole-pieces *b*² are riveted or otherwise secured, see Fig. 9, said projecting ends of the cores being preferably shouldered and the reduced portions thereof extended through holes in the pole-pieces. Said pole- 100 pieces are made as flat plates, secured to the under side of the base *a*, by screws or oth-

erwise. The magnet-cores are thus rigidly secured to the base. The pole-pieces b^2 may be formed integral with the cores, if desired, as shown in Fig. 9. The magnet-coils b are 5 removably placed on the cores b' , so that other coils may be substituted therefor of the same or of different resistance and the exchange quickly and easily made. These coils are wound on spools of insulating material, see Fig. 12, comprising tubes b^3 having heads b^4 , said tubes being adapted to fit upon the cores. The coils are or may be covered with rubber shields b^5 to protect them from harm. A plate b^6 having spring- 10 acting end portions b^7, b^7 , is attached to the under side of the back-piece c , its end portions engaging the ends of the shields and acting by pressure thereupon to press the magnet-spools down upon the base and prevent them from sliding up and down. Said plate b^6 also has downwardly extended projections b^8 , see Fig. 13, which enter holes in the ends of the shields and prevent said shields and the magnet-coils therein from 15 turning and thereby straining upon the electric-wire connections. The back piece or heel-piece c of the magnet is attached to the upper ends of the cores b' by bolts or otherwise, and a bridge c' is attached to said 20 back-piece by screws or otherwise. The back-piece is extended at each end a short distance beyond the coils to provide for the attachment thereto of the bridge, so that a long bridge may be employed. The bridge 25 c' has at each end a short arm c^2 , extended rearwardly, by which it is attached to the back-piece, so that the main portion of the bridge will be offset or caused to project forward with respect to the magnet-coils. The 30 bridge c' also has at each end an arm c^3 , extended forwardly, and said arms respectively support two binding-posts for the magnet-wires c^4 , and the leading-in wires c^5 . These binding-posts may be of any suitable 35 construction, so far as my present invention is concerned, but the particular form herein shown forms the subject-matter of my divisional application for Letters Patent Serial No. 535,432, filed December 29, 1909.

40 The bridge is formed or provided with a flat surfaced portion at or near its middle to which an indicating-plate e may be detachably secured. This plate may have marked thereon the resistance of the relay.

45 The bridge also has secured to it, along its middle, a block e' of insulating material to which is secured a metal plate e^2 , bearing two binding-posts e^3, e^3 , of any suitable construction, and the inside wires or connecting

50 magnet-wires e^4, e^4 , which lead respectively from the two magnet-coils are connected respectively to said binding-posts. The inside magnet-wires e^4 are each made long enough to be connected to the binding-posts

d of the bridge, so that in case either magnet-coil should become disabled it may be removed and the remaining coil connected in circuit for use. As it sometimes happens that one coil only is disabled, provision for using the other coil is important. 65 Providing two binding-posts e^5, e^5 , one for each inside magnet-wire e^4 , permits either wire to be separately disconnected, but in lieu thereof a single binding-post may be employed to which both inside magnet-wires 70 are connected, as shown in Fig. 11.

The armature f is arranged on the under side of the base a of the supporting-bracket. It is secured to the upper side of a plate f' by an insulated support f^2 , or otherwise, 80 and said armature-carrying-plate f' has at or near each end, at its rear edge, an ear f^3 which extends rearwardly and upwardly and bears a pivot-screw f^4 , the conical end of which engages an adjusting-screw f^5 , see 85 Figs. 4 and 5, which is formed with a socketed end to receive the end of the pivot-screw f^4 , so that the armature-carrying-plate is pivotally supported. The adjusting-screws f^6 , which serve as bearings for the pivot-screws, are contained each in a sleeve f^50 , and said sleeves are tightly held by being clamped in split-lugs f^8 , formed or arranged on the under side of the base a , the upper and under parts of which are connected together adjustably by screws f^7 . By arranging the pivot at the rear edge of the armature-carrying-plate, said plate and armature borne by it are adapted to move in an arc of considerable radius and by extending said ears upwardly a short distance the engaging-face of the armature can be disposed in line with the centers of the pivots. The split lugs f^8 may be formed integral with the base a , as shown in Fig. 8, or integral with the pole-pieces b^2 , as shown in 90 Figs. 6 and 7, or integral with the pole-pieces and cores, as shown in Fig. 9. The armature-carrying-plate f' has extended from it, in a forward direction, an extension or arm f^9 , which occupies a position between two adjusting-screws f^9, f^{10} , preferably having insulated points, said screws limiting the movement of said plate in opposite directions. The adjusting-screw f^9 is 95 screwed into the base a , and the adjusting-screw f^{10} extends through a cross-piece f^{12} , secured by screws or otherwise to post f^{13} , which are arranged on the under side of the base a , and extend downwardly a short 100 distance.

The electro-magnet thus shown is especially arranged to be disposed with the base of its supporting-bracket in a horizontal plane, but it is obvious that it may be otherwise disposed.

All of the movable parts are or may be enclosed in a glass or other globe m , which

is fitted against the under side of the base *a*, and for the purpose of providing a tight joint a groove is formed in said base, see Fig. 14, in which is placed a rubber gasket *m*, and the edge of the globe engages said gasket. A rib may be arranged at the bottom of said groove against which the gasket is pressed.

As here shown, a post *m*² extends downward from the cross-bar *f*¹², and through a hole in said globe, and the end of said post is threaded and receives upon it a nut *m*³, by which the globe is securely held in place.

A sealing-wire *m*⁴ may be fastened to the extremity of the post, outside of the nut, to prevent the removal of the nut and also of the globe, thereby obviating the liability of the moving parts being tampered with.

The moving parts are thus contained in a substantially water-tight compartment and will not be affected by the elements when exposed to the weather, thus especially fitting the electro-magnet for use in a relay adapted for out-of-door service.

Before sealing the globe the device may be tested and a test-tag secured thereto, in some conspicuous place, within the globe, so that when sealed the fact that it has been tested and the name of the tester may be indicated.

In lieu of securing the globe to the base by a single-screw, other means may be employed. In lieu of a globe a skeleton-frame may be constructed, see Figs. 16 and 17, wherein *n* represents a metallic-ring which is secured to the under side of the base *a*, by posts *n*', and the space between said ring and the base closed by a glass cylinder *n*², and a circular door *n*³, having a glass face may be arranged upon or otherwise secured to said ring.

If it is desired to inclose the magnet-coil itself, a glass globe of the form shown in Fig. 15, may be employed, wherein it will be seen that a globe *o* is arranged on top of the base *a* and the binding-posts *d*, *d*', to which the leading-in wires for the magnet are connected are arranged on said base in front of the magnet-coils.

Having thus described my invention, what I claim as new and desire to secure by Letters Patent is:—

1. In an electro-magnet, a base, magnet cores extending from and secured at their lower ends to the base, magnet coils including spools on which the coils are wound removably arranged on said cores beyond the base, means engaging the cores for normally holding the coils against removal from the cores, a bridge carried by said means and having binding posts for respectively receiving the leading-in wires, the magnet wires, and the connecting wires for the coils, said connections being shiftable

to admit of the cutting out of either coil, said means supporting all of said connections and being movable to permit removal of either coil without interfering with the operation of the relay.

2. In an electro-magnet, a base, magnet cores extending from and secured at their lower ends to the base, magnet coils removably arranged on the cores, a back-piece removably engaging the cores beyond the coils and preventing removal of the coils, a bridge carried by the back-piece, and binding posts carried by the bridge for receiving the leading-in wires, the magnet wires, and the connecting wires for the coils, the arrangement of the connections permitting their being shifted to cut out either coil, the back-piece and connected parts being movable as a unit to permit removal of either coil without interfering with the operation of the relay.

3. In an electro-magnet, a base, magnet cores extending from and secured at their lower ends to the base, magnet coils removably arranged on the cores, a back-piece removably engaging the cores beyond the coils and securing the coils against removal, a bridge carried by the back-piece, binding posts carried by the bridge for receiving the leading-in wires, the magnet wires, and connecting wires for the coils, and means whereby the connecting wire from either coil may be disconnected from the connecting wire of the other coil and connected to the binding post of such other coil to thereby cut out such other coil, the back-piece and all connected parts being movable as a whole to permit removal of either coil at will without interrupting the function of the other coil.

4. In an electro-magnet, a horizontally arranged base having holes through it, upright magnet-cores fixedly connected with the base, the lower ends of which project through the holes therein, enlarged pole-pieces on the lower ends of said cores below the base, removable magnet-coils arranged on said upright cores which rest on the base, a back-piece attached to the upper ends of said cores above the coils, and means connected with said back-piece and arranged to exert a downward pressure on said coils to hold them in position on the base, substantially as described.

5. In an electro-magnet, a base having holes through it, magnet-cores having their lower ends extended through the holes in said base, enlarged pole-pieces on the ends of said core below the base, means to fixedly connect the lower ends of said cores to the base, with the pole-pieces in engagement with the under side of the base, removable magnet-coils arranged on said cores which rest on the top of the base, and removable

- means engaging said coils for holding them in position on the base, substantially as described. 65
6. In an electro-magnet, a stationarily supported pair of magnet-cores, magnet-coils removably placed thereon, a back-piece connected to said cores, and a spring-plate interposed between said back-piece and coils for holding said coils in place, substantially as described. 70
7. In an electro-magnet, a stationarily supported pair of magnet-cores, magnet-coils removably placed thereon, hollow shields removably placed on said coils, a back-piece connected to said cores, and a spring-plate attached to the under side of said back-piece, the ends of which bear upon the ends of said shields, and act to hold said shields and the coils inclosed thereby, in place, substantially as described. 75
8. In an electro-magnet, a stationarily supported pair of magnet-cores, magnet-coils removably placed thereon, hollow shields removably placed on said coils, a back-piece connected to said cores, and a spring-plate attached to the under side of said back-piece, the ends of which bear upon the ends of said shields, and act to hold said shields and the coils inclosed thereby, in place, said spring-plate having means to engage said shields to prevent same from turning, substantially as described. 80
9. In an electro-magnet, a stationarily supported pair of magnets having a back-piece, a bridge having rearwardly extended arms engaging said back-piece, and binding-posts supported by said bridge to which the magnet-wires and leading-in wires are attached, substantially as described. 85
10. In an electro-magnet, a stationarily supported pair of magnets having a back-piece, a bridge having rearwardly extended arms engaging said back-piece, and also having forwardly extended arms, and binding-posts arranged on said forwardly extended arms to which the magnet-wires and leading-in wires are attached, substantially as described. 90
11. In an electro-magnet, a pair of magnets having a back-piece, a bridge attached to said back-piece, binding-posts supported by said bridge to which the magnet-wires and leading-in wires are respectively connected, connecting-wires between the coils of the magnets, a metallic support on said bridge, and means thereon to detachably engage the ends of said connecting-wires and electrically connect them together, substantially as described. 95
12. In an electro-magnet, a pair of magnets having a back-piece, a bridge attached to said back-piece, binding-posts supported by said bridge to which the magnet-wires and leading-in wires are respectively connected, connecting-wires between the coils of the magnets, a metallic support on said bridge, and means thereon to detachably engage the ends of said connecting-wires and electrically connect them together, substantially as described. 100
13. In an electro-magnet, means to pivotally support the armature, consisting of a supporting-plate upon the upper side of which the armature is secured, ears extended upwardly from the rear part of said plate, at opposite ends thereof, for the pivots, pivotal connections for the plate, and adjustable clamping and holding members for said pivotal connections which are arranged on the base. 105
14. In an electro-magnet means to pivotally support the armature, consisting of a supporting plate for said armature, pivot-screws projecting from said plate, adjusting-screws having socketed ends which receive the aforesaid pivot-screws, externally-threaded sleeves arranged on the base having internally-threaded sockets to receive said adjusting-screws, substantially as described. 110
15. A support for an electro-magnet consisting of a bracket comprising a base adapted to support the magnets on its upper side, and an armature on its under side, said base having an upright rising from its rear edge adapted for detachable connection with a back-board, and having on its under side a packing-ring, a globe arranged at the under side of the base inclosing the armature, the edge of which engages said packing-ring, 115 said globe having a center-hole, a post connected with the base and extended through the center-hole in said globe, and having a screw-threaded end with a nut arranged thereon which holds the globe in firm engagement with the packing-ring, substantially as described. 120
16. A support for an electro-magnet consisting of a bracket comprising a base adapted to support the magnets on one side thereof, and the armature on the opposite side thereof, having an upright rising from it, and a transparent globe arranged at said opposite side of the base inclosing the armature, comprising a bottom wall and upright side walls, and having a center-hole, a post connected with the base which extends through said hole, and means arranged on said post and engaging the globe for holding the globe in place, substantially as described. 125
17. A support for an electro-magnet consisting of a bracket comprising a base adapted to support the magnets on one side thereof, and the armature on the opposite side thereof, having an upright rising from it, a transparent globe arranged at the under side of said base inclosing the armature, a frame on said base, a center-support for said

- globe connected with said frame, having a screw-threaded end, and a nut on said center-support for holding the globe in place, substantially as described.
- 5 18. A support for an electro-magnet consisting of a bracket comprising a base adapted to support the magnets on one side thereof, and the armature on the opposite side thereof, having an upright rising from it,
- 10 a transparent globe arranged at said opposite side of the base inclosing the armature, a center-support for said globe, a cross-bar
- bearing said center-support which bridges the armature, and means for detachably connecting the globe with said center-support, 15 substantially as described.

In testimony whereof, I have signed my name to this specification in the presence of two subscribing witnesses.

ALFRED A. ZIEGLER.
